UNITED STATES PATENT OFFICE.

ASA ASHWORTH, OF SALAMANCA, NEW YORK, ASSIGNOR, BY DIRECT AND MESNE ASSIGNMENTS, TO INTERNATIONAL TEXTILE DEVICES, INC., OF SALAMANCA, NEW YORK.

YARN CLEANER.

Application filed April 5, 1921. Serial No. 458,725.

To all whom it may concern:

Be it known that I, ASA ASHWORTH, a citizen of the United States, residing at the town of Salamanca, in the county of Cattaraugus and State of New York, have invented certain new and useful Improvements in Yarn Cleaners, of which the following, taken in connection with the accompanying drawings, is a specification.

10 The invention relates to devices for removing "slubs," bad piecings, thickened portions, etc., from the yarn. Such thickened portions form bad imperfections in the woven cloth if woven into the fabric.

15 The object of the improvement is to provide a simple and easily threaded yarn cleaner which will invariably catch the slubs, bad pieces or other imperfections in the yarn, different sized openings being 20 provided for different size threads so that the yarn must be substantially uniform as to size in order to pass through the opening in the slab catcher, which is a fixed tubular opening as to its size so that it cannot be 25 changed by the draw of the yarn, being preferably funnel-shaped at the mouth so that the yarn will enter freely; and the invention consists in the novel features and combinations hereinafter set forth and 30 claimed.

In the drawings, Figure 1 is an end elevation of the winding machine for the yarn, showing the slab catchers on each side with the yarn broken on one side by a slab entering the catcher. Fig. 2 is a top plan view of the slab catcher mechanism showing the yarn as it passes through the same. Fig. 3 is a sectional view at line 3—3 in Fig. 2 showing a rear elevation of the slab catcher 35 with the closed or locked small yarn opening therethrough, the V-shaped threading opening being turned away from said yarn opening thereby closing the same. Fig. 4 is a detail elevation of the split ring around 40 said central portion; and Fig. 5 is a sectional view of said ring at line 5—5 in Fig. 4 showing the construction and arrangement of said ring. Fig. 6 is a front elevation of the round central portion of the slab 45 catcher; and Fig. 7 is a side elevation of the same, part being shown in section in order to show the grooved opening for the yarn as it is drilled through the edge portion of the same so that when the outer ring is

placed upon the same, it closes and perfects 55 the shape of said yarn opening; and Fig. 8 is a rear elevation of said inner portion showing the three graduated yarn openings therein. Fig. 9 is a front elevation of the slab catcher head mounted upon the support bar, the outer ring being turned into the threading position; and Fig. 10 is a sectional view at line 10—10 in Fig. 9 showing the preferred construction and arrangement 60 of the same. Fig. 11 is an elevation of enlarged segments of the outer ring and round central portion showing the correct formation of the peripheral slotted round hole for the yarn to draw through, and the entrance 65 to the same.

70 Like characters of reference refer to corresponding parts in the several views.

The numeral 15 designates the winding machine for the yarn which has the spool 75 holders and winding mechanism on opposite sides in the usual manner, except that I attach the support bars 16 to the rack 17 at each side so as to give said support bars 16 great rigidity as they extend out from said 80 rack 17.

The support bars 16 have the preferably 85 porcelain spools 18 attached thereon in line with the slab catcher opening for the yarn. The outer end 19 of each bar 16 is turned at an angle to support thereon the slab arresting mechanism 20, which consists of the inner disk-shaped piece 21 with its threaded 90 extension 22 for attachment to the end 19 of the support bar 16 by means of a suitably threaded nut. The round piece 21 is provided with a flange 23 to hold it in position within the outer severed ring 24 which rotatively fits around the piece 21.

The ring 24 has the Y-shaped opening 25 95 therein for threading the yarn into the yarn hole in the central part 21. The Y-shaped opening 25 is shaped so as to invariably guide the yarn into said opening without catching before entering the yarn hole. The ring 24 has the handle 26 for manually 100 turning the same, which handle is so placed as to automatically turn said ring 24 back to the locking position and assist in holding the same in said locking position. The ring 24 is also provided with the spaced stop pins 27 which engage the opposite sides of a stop pin 28 on the angular end 29 of the support bar 16 to thereby limit and guide the 105

rotative movement of the ring 24 so that when said ring is turned by the handle 26, it is accurately stopped with said Y-shaped opening in exact position over the slotted opening to the yarn hole in the central portion 21.

The central round or disk-shaped piece 21 has the three drilled openings 29, 30 and 31 therein with the slot extending from said 10 drilled openings to the periphery of the flange 23, said holes or openings being drilled through the lengths of the piece 21, so near its periphery as to be easily slotted into, yet form a smooth round hole when 15 closed by turning the ring 24. A porcelain tip 32 on the strap piece 34, having the guide notch 33 therein for the yarn 37, is pivotally attached by metal strap piece 34 to piece 21 by the central screw 35. The end screw 36 20 and the central screw 35 hold the guide notch 33 firmly in position opposite whichever one of the holes 29, 30 or 31 is desired according to the size of the yarn 37, additional screw holes 38 and 39 being provided 25 in the face of the round plate or piece 21 in alinement with the different notched openings 29, 30 and 31 for the screw 36 in placing the guide 32.

It is now apparent that the Y-shaped 30 threaded openings 25 can be turned opposite the uppermost one of the slotted drilled openings 29, 30, 31 according to which one of the latter is used as determined by the size of the yarn, said drilled openings being 35 preferably made substantially as follows: The smallest drilled opening 29 is made by about a No. 60 standard drill and accommodates the yarn between sizes 35 and 50. The drilled opening 30, which is preferably 40 drilled by about a No. 55 standard drill accommodates the different sizes of yarn from 20 to 35; and the largest drilled opening 31 is made by about a No. 50 standard drill, and accommodates the sizes of yarn from 45 about 5 to 20, being so adapted as to size that said yarns will freely pass through said drilled openings.

The openings 29, 30 and 31 define walls 50 which function as thread gaging means, which means have each a radial inlet, the latter closed by the inner circumference of the ring 24 in one position of the latter.

The ring 24 is freely rotative upon the central piece 21 which is firmly attached on 55 the ends 19 so that said ring can be manually turned into alinement with the desired notched and drilled opening. The yarn 37 is then quickly and easily passed into the notch 25 and drilled opening 29, 30 or 31 60 according to the size of said yarn, after which the ring 24 is turned to the locking position, as shown in Fig. 3, leaving the yarn in the desired size closed hole or drilled 65 yarn opening in position on the angular end 19 of the support bar 16. The inner

edge 40 of the ring 24 is rounded slightly, as shown, so as not to cut or wear upon the yarn as it runs swiftly through the slab arrester, giving the yarn hole a slight funnel shape as shown in Fig. 10.

It is now obvious that when a thickened portion or slab as shown at 41 in Fig. 1 attempts to pass through the small drilled hole of the correct size for the size yarn, it will be instantly stopped and the yarn 37 70 will break down as shown at 42, permitting the operator to break out the slab or thickened portion and retie or draw a knot in the yarn, rethreading the slab arrester and passing the thread over the spool 18 and down 75 around the porcelain spool or pulley 43 and thence up to the winding mechanism 44.

The preferred form of the drilled yarn hole 29, 30 or 31 is shown in the enlarged view in Fig. 11, which shows the Y-shaped 80 guide slot 25 in the ring 24 and the same size slot through the flange 23 of the round central portion 21. The upper stop pin 27 is so placed in relation to the stop pin 28 that said slots are stopped in perfect alinement. All entrances to holes or openings 85 of any shape for the yarn should be rounded or slightly funnel-shaped so as not to roughen the yarn as it passes through or over the same.

What is claimed is:—

1. In combination with a thread engaging member having an eye and a perimetric inlet leading into the eye, a closure for the inlet having a flared entrance which in one 100 position registers with the inlet to thereby allow the thread to be moved through the entrance and inlet and into the eye and which in a second position extends over the inlet to close same.

2. In a thread guide and slab catcher, a pair of relatively movable means one of which has a thread-receiving gage with an inlet and the other of which means has a part which is complementary to the gage in one position and closes the inlet and having a part which in a second position of the means opens the inlet.

3. In combination with thread gaging means having an inlet, locking means for said inlet formed to close the latter in one position and in a second position to open the inlet to allow thread to be moved into the gaging means.

4. In combination with a winding machine, a plate supported thereon having a hole near the peripheral edge thereof for the yarn to run through, said hole having a sidewise slot from the periphery of said plate to said hole to thread the yarn thereinto, and means for closing said slot overlying the same.

5. In combination with a winding machine, a plate supported thereon having a plurality of different sized yarn holes drilled 130

therethrough near the periphery of the same and slots from said holes to said periphery to thread the yarn into said holes through said slots, and a common means 5 overlying and for closing each of said slots near their entrance to the respective holes.

6. In combination with a winding machine, a round plate supported thereon having a plurality of different sized yarn holes 10 therethrough near the periphery thereof and slots from said holes to said periphery, and a rotatable ring around said round plate to close said slots near the entrance to said 15 yarn holes.

7. In combination with a winding machine, a round plate supported thereon having a plurality of different sized yarn holes 20 therethrough near the periphery thereof and slots from said holes to said periphery, a 25 rotatable ring around said round plate to close said slots near the entrance to said yarn holes, and a Y-shaped guideway through said ring to the slot in the desired size yarn hole to thread the yarn into the same.

8. In combination with a winding machine, a round plate supported thereon having a plurality of different sized yarn holes 30 therethrough near the periphery thereof and slots from said holes to said periphery, a 35 rotatable ring around said round plate to close said slots near the entrance to said yarn holes, a Y-shaped guideway to the slot in said yarn hole through said ring to enter the yarn, and stops on said ring and 40 said support for said ring to stop said Y-shaped guideway in said ring opposite the slot to said yarn hole.

9. In combination with a winding machine, a slab catcher comprising a round plate having a plurality of different sized 45 yarn holes therethrough near the periphery thereof and slots from each of said yarn holes to said periphery to enter the yarn 50 into said yarn holes, a ring rotatably confined on said round plate having a Y-shaped crosswise guideway therethrough to said slotted yarn holes, a stop for said slab catcher, spaced stops on said ring, one of

way opposite the slot to the desired yarn hole substantially as and for the purpose specified.

10. In combination with a winding machine, a slab catcher comprising a round 55 plate having a plurality of different sized yarn holes therethrough near the periphery thereof and slots from each of said yarn holes to said periphery to enter the yarn into said yarn holes, a ring rotatably confined on said round plate having a Y-shaped crosswise guideway therethrough to said slotted yarn holes, a stop for said slab catcher, spaced stops on said ring, one of 60 said stops on said ring placing said guideway opposite the slot to the desired yarn hole and the other stop closing said yarn hole, a handle on said ring to manually turn the same, and a porcelain tipped guide 65 attachable on the face of said round plate opposite said yarn holes to run the yarn thereover and through one of said holes.

11. In combination with thread gaging means including an eye having a perimetric inlet, a rotatable lock having a thread receiving part which latter in one position of the lock is out of register with said inlet to lock the thread against egress from the 70 eye.

12. In combination with a rotatable member 80 having a series of thread eyes and a perimetric inlet for each eye, a lock having a thread-receiving slot movable into and out of register with the inlets.

13. In combination with a member having a thread guide eye and a perimetric inlet therefor, a rotatable lock having a part movable across the inlet to close same in one position and in a second position to expose the inlet to allow thread to be moved there- 85 through and into the eye.

14. In combination with thread gaging means having an inlet, gravity responsive means for normally closing said inlet.

In testimony whereof I have affixed my 90 signature in the presence of two witnesses.

ASA ASHWORTH.
